REAMER

John H. Howard, Huntington Park, and Alfred C. Catland, Alhambra, Calif.; said Catland assignor to Globe Oil Tools Company, Los Nietos, Calif., a corporation of California

Application April 13, 1936, Serial No. 74,166

10 Claims. (Cl. 255—73)

This invention relates to a well drilling tool and relates more particularly to a well reamer. A general object of the invention is to provide a practical, effective well reamer for reaming or 5 enlarging a pilot bore and for forming a smooth regular seat on the wall of the well to receive the packer of a formation tester, or the like.

Many formation testers or well testers embody 10 a packer designed to seal with an inclined shoulder of earth formation in the well. Heretofore it has been the general practice to employ a drag or scrape type tool to form the inclined shoulder in a well to receive the packer of a tester. Drag type or scrape type drilling tools are

15 not capable of forming a smooth regular shoulder for engagement by a packer.

Another object of this invention is to provide 20 a well tool of the reamer type embodying roller cutters positioned and mounted to form a smooth regular inclined shoulder on the wall of the well for properly receiving the packer of a well tester or the like.

Another object of this invention is to provide 25 a well reamer embodying roller cutters and that is operable to enlarge a rat-hole or pilot bore to the desired full gauge.

Another object of this invention is to provide 30 a well drilling tool embodying a pilot bit operable to guide the tool in a previously formed pilot bore or to drill a pilot bore and that embodies reaming roller cutters rotatable about inclined axes operable to enlarge the pilot bore to the desired gauge.

Another object of this invention is to provide 35 novel and particularly effective means for rotatably supporting the roller cutters of a well reamer.

Another object of this invention is to provide 40 a well reamer embodying a simple one diameter pin rotatably supporting the roller cutters and a simple dependable means for locking the pin against movement and displacement.

Another object of this invention is to provide 45 a well reamer of the character mentioned in which the cutter carrying pins are supported at their ends and at points between their ends.

A further object of this invention is to provide 50 a well reamer that is very simple and inexpensive and that is easy to recondition after use.

55 The various objects and features of our invention will be fully understood from the following detailed description of a typical preferred form and application of the invention, throughout which description reference is made to the accompanying drawings, in which:

Fig. 1 is a side elevation of the improved tool provided by this invention. Fig. 2 is an enlarged longitudinal detailed sectional view of the reamer portion of the tool, being a view taken substantially as indicated by line 2—2 on Fig. 5. Fig. 3 is an enlarged transverse detailed sectional view taken as indicated by line 3—3 on Fig. 1. Fig. 4 is an enlarged transverse detailed sectional view taken as indicated by line 4—4 on Fig. 1. Figs. 5 and 6 are transverse detailed sectional views taken as indicated by lines 5—5 and 6—6, respectively, on Fig. 2, and Fig. 7 is an enlarged fragmentary detailed sectional view taken as indicated by line 7—7 on Fig. 2.

The well tool provided by this invention includes, generally, a shank 10, a bit 11 on the lower end of the shank, removable inclined pins 12 and 12^a on the shank 10 above the bit 11, means 13 locking the pins 12 and 12^a in place, and roller cutters A and B rotatable on the pins 12 and 12^a respectively.

The shank 10 is the mandrel or body of the tool and is adapted to be secured to the lower end of a well drilling string. The shank 10 is an elongate member and is provided at its upper end with means for connecting with the drilling string. In the case illustrated in the drawings a tapered screw threaded pin 14 is provided on the upper end of the shank 10 for connecting the shank with the drilling string. The shank 10 is provided with a downwardly and inwardly tapered portion 15. The tapered portion 15 is spaced some distance above the lower end of the shank 10. An annular rim or flange 16 is provided at the upper end of the portion 15 and a similar flange 17 of less diameter is provided at the lower end of the portion 15. The lower portion of the shank 10 below the flange 17 is reduced in diameter and may be graduated in diameter, as illustrated. A central longitudinal fluid passage 9 extends longitudinally through the shank 10 from one end to the other.

In accordance with the invention the shank 10 is shaped or formed to carry the pins 12 and 12^a and the cutters A and B. Circumferentially spaced sets or series of recesses 18 and 19 are provided in the tapered portion 15 of the shank 10. In the preferred construction there are three equally spaced series of recesses. At least one of the series has two vertically spaced recesses 18 and at least one of the series has three vertically spaced recesses 19. In the preferred form of the invention illustrated in the drawings there are two vertically spaced recesses 18 in two of the series and three vertically spaced recesses 19 in

the third series of recesses. The upper ends of the uppermost recesses 18 and 19 occur at the flange 16. The lower ends of the lowermost recesses 18 and 19 occur at the flange 17. The recesses 18 are of the same length and adjacent recesses 18 are separated by partitions or webs 20. The webs 20 are integral parts of the shank 10. The recesses 19 of the third series of recesses may be of substantially the same size and are separated or spaced by integral webs 21 of the shank 10. In accordance with the invention the inner walls of the recesses 18 and 19 are inclined downwardly and inwardly relative to the longitudinal axis of the shank 10. Portions of the walls of the lowermost recesses 18 and 19 may be substantially vertical. In the preferred construction the inner walls of the other recesses 18 and 19 are curved about downwardly and inwardly inclined axes of curvature. The upper and lower walls of the recesses 18 and 19 are flat and may be normal to the axes of curvature of the inner walls of the recesses. The recesses 18 and 19 are related so that the middle or intermediate recess 19 lies in a horizontal plane or zone overlapping the adjacent end portions of the upper and lower recesses 18. Ports 8 are provided in the shank 10 to conduct the circulation fluid from the passage 9 to the recesses 18 and 19. There may be a port 8 communicating with each recess 18 and 19 to assure the proper flushing of the cutters A and B. If desired the fluid passage 9 may be of downwardly diminishing diameter as illustrated in Fig. 2.

The bit 11 may be employed to drill a pilot bore 35 in advance of the reaming cutters A and B or may be employed to operate in a previously formed pilot bore to guide the tool. In accordance with the broader aspects of the invention the bit 11 may be varied considerably in character and may 40 be secured to the shank 10 in any suitable manner. The particular bit 11 illustrated in the drawings is a drag type or scrape type bit comprising a stem 22 and cutting blades 23 projecting from the lower end of the stem 22. In the 45 drawings we have shown the bit 11 secured to the shank 10 by a practical effective bayonet type connection, it being understood that the bit 11 may be threaded to the shank if desired. In the structure illustrated in the drawings a longitudinal socket 24 is provided in the stem 22 to receive the reduced lower portion 10a of the shank 10. L-shaped slots or bayonet slots 25 are provided in the stem 22 to receive lugs 26 on the shank portion 10a. The lugs 26 are adapted to 50 55 cooperate with the lateral portions of the bayonet slots 25 to connect the bit 11 to the shank 10. Keys 27 are inserted in the longitudinal or vertical portions of the slots 25 behind the lugs 26 to lock the lugs in the lateral portions of the slots. 60 Screws 28 are threaded in the shank to hold the keys 27 against upward displacement. The bit 11 has one or more fluid discharge ports (not shown) for discharging the circulation fluid delivered to the bit by the fluid passage 9.

65 The pins 12 and 12a are provided to rotatably carry the cutters A and B and are removably secured to the shank 10 to extend through the series of recesses 18 and 19. There is a pin 12 extending through each series or set of recesses 70 18 and a pin 12a extending through the series of recesses 19. The pins 12 and 12a are plain cylindrical members of the desired diameter. In accordance with the invention the cutter carrying pins 12 are inclined downwardly and inwardly 75 relative to the longitudinal axis of the shank 10.

Sockets 29 are provided in the shank flange 17 at the lower ends of the lowermost recesses 18. The longitudinal axes of the sockets 29 are inclined downwardly and inwardly and the lower ends of the sockets 29 are closed. Openings 30 extend through the flange 16 at the upper ends of the uppermost recesses 18. The openings 30 are inclined downwardly and inwardly and are longitudinally aligned with the sockets 29. Partially cylindrical grooves 31 are provided in the webs 10 20. The axes of curvature of the walls of the grooves 31 are coincident with the axes of the sockets 29 and openings 30. The pins 12 are passed downwardly through the openings 30 to have their lower end portions received in the sockets 29. The bottoms of the sockets 29 may limit the downward movement of the pins 12. The pins 12 bear in or cooperate with the grooves 15 31 and are thus supported against inward pressures between their ends. The upper ends of the pins 12 are preferably within the openings 30. 20

A socket 32 is provided in the flange 17 at the lower end of the lower recess 19. The socket 32 is inclined downwardly and inwardly relative to the longitudinal axis of the shank. An opening 33 is provided in the flange 16 at the upper end of the upper recess 19. The opening 33 is inclined downwardly and inwardly and is in longitudinal alignment with the socket 32. Partially cylindrical grooves 34 are provided in the webs 21. The axes of curvature of the walls or grooves 34 are coincident with the axis of the socket 32 and the opening 33. The pin 12^a is passed downwardly through the opening 33 to have its lower portion received in the socket 32. The upper end of the pin 12^a is preferably within the opening 33. The pin 12^a extending through the recesses 19, cooperates with the grooves 34 to be supported against inward thrusts at spaced points between its ends. It will be observed that the pins 12 and 12^a arranged as just described are held against movement in all directions except about their own axes and upward movement.

The means 13 operates to lock or hold the pins 12 and 12^a against upward movement and against turning about their axes whereby the pins are held against displacement from the shank 10. The pin retaining means 13 includes a block 36 secured to each web 20. The webs 20 each have a flat sided key 37 and a flat walled slot or groove 38 is provided in the inner side of each block 36 to receive a key 37. The cooperation of the keys 37 and the grooves 38 holds the blocks 36 against lateral movement. A flat walled slot 39 is provided in the inner side of each block 36 to cooperate with a pin 12. In accordance with the invention the pins 12 each have a flat walled notch 40 for cooperating with a slot 39. The cooperation of the walls of the slots 39 and the notches 40 holds the pins 12 against rotation. The upper 60 and lower ends of the blocks 36 cooperate with the end walls of the notches 40 to hold the pins 12 against longitudinal movement. It is to be understood that the lower ends of the pins 12 may cooperate with the bottom walls of the 65 sockets 39 to prevent downward movement of the pins. Means is provided for removably securing the blocks 36 to the shank 10. Screws 41 are passed through openings 42 in the blocks 36 and are threaded into openings 43 in the webs 20 and the adjacent parts of the shank 10. In practice the screws 41 may be socket headed and their heads may be received in the enlarged outer portions of the openings 42. The heads of the screws 41 may be peened over in the openings 42 70 75

to hold the pins against displacement. It is believed that it will be apparent how the cooperation of the slots 38 in the blocks 36 with the pin notches 40 effectively and dependably holds the pins against movement and displacement.

The pin retaining means 13 includes blocks 44 secured to the webs 21. Flat sided keys 45 are provided on the webs 21 and cooperate with grooves 46 in the blocks 44 to hold the blocks 10 against lateral shifting. In accordance with the invention flat walled slots 47 are provided in the blocks 44 and flat walled notches 48 are provided in the pin 12^a to cooperate with the slots 47. The engagement of the walls of the slots 47 and notches 48 holds the pin 12^a against rotational movement. The ends of the blocks 44 are adapted to cooperate with the end walls of the notches 48 to hold the pin 12^a against longitudinal movement. Suitable means is provided for removably 20 securing the blocks 44 to the webs 21. In the particular case illustrated screws 49 are passed through openings 50 in the blocks 21 and thread into openings 51 in the webs 21 and the adjacent parts of the shank 10. The screws 49 may be 25 socket headed screws. The heads of the screws 49 may be received in the enlarged outer ends of the openings 50. The heads of the screws 49 may be peened over in the openings 50 to prevent loss or unthreading of the screws 49. The blocks 44 30 cooperate with the pin 12^a to prevent rotational and longitudinal shifting of the pin and to maintain the pin in bearing cooperation with the grooves 34.

The roller cutters A are rotatable on the pins 35 12 to project from the mouths of the recesses 18 while the roller cutters B are rotatable on the pin 12^a in the recesses 19. The cutters A and B are in the nature of substantially cylindrical roller cutters. The upper portions of the uppermost 40 cutters A and B may be tapered. The lower end portions of the lower cutters A and B may be tapered as illustrated in the drawings. The cutters A and B have suitable clearance with the walls of their respective recesses 18 and 19 and project from the mouths of the recesses to 45 cooperate with the earth formation. The cutters A and B have suitable teeth or cutting parts. In the particular form of the invention illustrated the cutting teeth of the cutters B are spiraled in a left hand direction and the cutting teeth of the cutters A in one series of recesses 18 are spiraled in a right hand direction. The cutting teeth of the cutters A in the other series of recesses 18 are straight or axial. This relationship of the 50 cutting parts of the cutters A and B is best illustrated in Fig. 1 of the drawings.

Thrust washers 60 are provided on the pins 12 at the opposite ends of the cutters A. The washers 60 are polygonal or flat sided. The 55 washers 60 at the upper ends of the uppermost cutters A cooperate with flat walled notches 61 in the upper walls of the upper recesses 18. The cooperation of the washers 60 with the notches 61 prevents turning of the washers. The washers 60 at the lower ends of the lower cutters A cooperate with flat walled notches 62 in the bottom walls of the lower recesses 18. The flat 60 sided washers 60 fitting the flat walled notches 62 are held against turning. The washers 60 70 which space the ends of the cutters A from the webs 20 cooperate with flat walled notches 63 in the blocks 36. The notches 63 receiving the flat sided washers 60 hold the washers against turning. Thrust washers 65 are provided on the 75 pin 12^a at the opposite ends of the several cut-

ters B. The thrust washers 65 in the upper end of the uppermost cutter B has nonrotatable cooperation with a flat walled notch 66 in the upper wall of the uppermost recess 19. The thrust washer 65 at the lower end of the lowermost cutter B is held against turning by its cooperation with a flat walled notch 67 in the bottom wall of the recess 19. The thrust washers 65 spacing the ends of the cutters B from the webs 21 and the blocks 44 are partially received in flat walled notches 68 in the blocks 44. The flat sided washers 65 seated in the flat walled notches 68 are held against turning on the pin 12.

In operation, the tool provided by the present invention may be employed to form or finish an inclined shoulder of earth formation at the upper end of a rat-hole or pilot bore. When used for this purpose the bit 11 enters the pilot bore to guide and steady the tool. The cutters 20 A and B are adapted to engage the formation at the upper end of the pilot bore to cut or provide a smooth regular inclined shoulder. The cutters A and B are related so that no ridges or grooves are formed on the shoulder. The 25 intermediate cutter B operates in a horizontal or circumferential plane which overlaps the adjacent end portions of the cutters A. The plurality of roller cutters independently rotatable about inclined axes are particularly effective in 30 forming a smooth regular shoulder in the well. The tool may be employed to ream or enlarge a previously formed pilot bore. When used for this purpose the bit 11 enters the pilot bore in advance of the cutters A and B to guide and 35 steady the tool. The cutters A and B act on the earth formation at the upper end of the pilot bore and as the tool is rotated and fed downwardly they operate to enlarge the bore. The cutters A and B are spaced and positioned 40 to be particularly rapid and efficient in their cutting action. If desired, the tool may be employed as a drilling tool, in which case the bit 11 operates to form a pilot bore in advance of the cutters A and B. As the bit 11 forms the 45 pilot bore the cutters A and B operating above the bit enlarge the pilot bore to the desired diameter.

The cutters A and B are effectively and dependably supported for rotation about their individual axes. The cutter supporting pins 12 and 12^a are simple cylindrical parts whose opposite end portions are directly carried in openings in the shank 10. The pins 12 and 12^a are supported intermediate their ends against the 50 operating thrusts. The webs 20 and 21 serve to brace and support the intermediate portions of the pins 12 and 12^a respectively. As described above, the slotted blocks 36 and 44 cooperate with the pins 12 and 12^a at the webs 20 and 21 55 to dependably lock the pins against movement. The blocks 36 and 44 are simple inexpensive parts and are easily secured to the shank. The blocks may be readily removed from the shank 10 to permit the removal of the pins 12 and 12^a 60 when it is desired to replace the cutters.

Having described only a typical preferred form and application of our invention, we do not wish to be limited or restricted to the specific details herein set forth, but wish to reserve to ourselves any variations or modifications that may appear to those skilled in the art or fall within the scope of the following claims:

Having described our invention, we claim:

1. A well tool comprising, a shank having re- 75

cesses, a socket at an end of one recess and an opening at an end of another recess, a web on the shank between the recesses, a pin extending through the recesses, cooperating with the web, having one end portion carried in the socket and having its other end portion carried in the opening, and a part on the web cooperating with the pin to hold the pin against longitudinal movement, and cutters in the recesses 10 rotatably supported by the pin.

2. A well tool including, a shank having a series of aligned spaced recesses, and openings at the opposite ends of said series, a pin extending through the recesses and having its portions carried in said openings, a part secured to the portion of the shank between the recesses to hold the pin against turning movement, and cutters on the pin rotatable in the recesses.

3. A well tool including, a shank having a series 20 of recesses and an opening at each end of said series, a part on the shank between the recesses, a removable pin extending through the recesses and having its end portions supported in the openings and supported between its ends by said 25 part, means on said part holding the pin against turning and moving longitudinally, and cutters in the recesses rotatably supported by the pin.

4. A well tool including, a shank having a series of recesses and an opening at each end of 30 said series, a part on the shank between the recesses, a removable pin extending through the recesses and having its end portions supported in the openings and supported between its ends by said part, means on said part holding the pin against 35 longitudinal movement, and cutters in the recesses rotatably supported by the pin, said means including a block secured to said part and cooperating with the pin.

5. A well tool including, a shank having a series 40 of recesses and an opening at each end of said series, a part on the shank between the recesses, a removable pin extending through the recesses and having its end portions supported in the openings and supported between its ends by said 45 part, a substantially flat surface on the pin, a member secured to said part and cooperating with the surface to hold the pin against movement, and cutters rotatably carried by the pin to project from the recesses.

6. A well tool including, a shank having a series 50 of recesses and an opening at each end of said series, a part on the shank between the recesses, a removable pin extending through the recesses and having its end portions supported in the openings and supported between its ends by

said part, the pin having a notch, a member attached to said part and cooperating with the notch to hold the pin against movement, and cutters rotatably carried by the pin to project from the recesses.

7. A well reamer comprising, a shank having a series of recesses, an opening at one end of the series and a socket at the other end of the series, a part on the shank between the recesses, a pin extending through the recesses having one end portion carried in the opening, having its other end portion carried in the socket and bearing against said part, the pin having a notch, a member removably secured to said part and cooperating with the notch to lock the pin in position, and roller cutters rotatable on the pin and projecting from the recesses.

8. A well reamer including, a shank, three circumferentially spaced pins on the shank inclined downwardly and inwardly relative to the longitudinal axis of the shank, three roller cutters on one of the pins, and two roller cutters on each of the other pins of greater length than the first mentioned cutters, the cutters on the said pins being related to overlap in their engagement with the formation.

9. A well reamer comprising, a shank having a series of vertically spaced recesses, a socket at the lower end of said series and an opening at the upper end of said series, said socket and opening being inclined downwardly and inwardly relative to the longitudinal axis of the shank, a pin extending through the recesses and having one end carried in the socket and one end carried in the opening, a member secured to the shank between the recesses and cooperating with the pin to hold it against longitudinal movement, and roller cutters in the recesses rotatable on the pin.

10. A well tool comprising, a shank having 40 circumferentially spaced series of vertically spaced recesses, sockets at the lower ends of said series, and openings at the upper ends of said series, the sockets and openings being inclined downwardly and inwardly relative to the longitudinal axis of the shank, pins passing through the recesses and bearing on the portions of the shank between adjacent recesses, and having their ends carried in the sockets and openings, blocks secured to said portions of the shank and holding the pins against turning, and roller cutters in the recesses rotatable on the pins.

JOHN H. HOWARD.

ALFRED C. CATLAND.

55
